SHAVING MACHINE

Filed Feb. 4, 1930

UNITED STATES PATENT OFFICE

FRANK WAYLAND, OF SALEM, MASSACHUSETTS

SHAVING MACHINE

Application filed February 4, 1930. Serial No. 425,810.

This invention relates to leather shaving machines of the kind employed in tanneries and other leather working establishments and relates more particularly to improvements in the feeding mechanism of such a machine.

In my copending application, Serial No. 384,635, filed August 9, 1929, I have disclosed one embodiment of feeding means in which a support, carrying a rigid feed roll, is movable bodily toward and from the cutter by means which applies the actuating force substantially in the plane of the movement of the feed roll, and which is adapted to lock the support unyieldingly in adjusted position.

While the aforesaid machine is highly effective for its intended purpose, I have found for certain work, for example, for shaving calf skins where the longitudinal central portion or back line is substantially thicker than the sides, that it is desirable to provide for a slight but accurately limited yielding of the bed or feed roll at a point or points intermediate its ends to accommodate such greater thickness, it being understood that with such an arrangement the skin is not reduced to uniform thickness throughout, but varies from center to edge.

To provide for such desirable mode of operation I contemplate the employment of a feed roll which, in accordance with one embodiment, may be a solid piece of steel or other suitable material but of such small diameter relative to its length that it will spring away from the cutter when the skin being shaved is abnormally thick at places. However, in order to control and adjust the amount of such spring of the roll, I prefer to provide one or more adjustable abutments for the roll, such abutments being provided, if desired, with anti-friction elements for engagement with the roll. Normally, but a single centrally disposed abutment is necessary, but I contemplate the provision of a plurality of abutments spaced longitudinally of the roll and independently adjustable so as to permit relief or application of the pressure exerted by the feed roll at any of such points in the length of the roll.

As an arrangement alternative to the solid feed roll above described, I may provide a

roll having a substantially rigid unyielding core (of steel for example) provided with an exterior sheathing of yieldable, preferably resilient material, such as rubber, and having mounted upon this sheathing a plurality of hard surfaced rigid and indeformable rings of steel, brass, or the like, each preferably of relatively small axial extent and spaced slightly from one another so as to permit each ring to move independently of the others. 55 With this construction the effective surface of the roll is constituted by the hard surfaced rings which individually maintain their normal circular curvature and which are thus capable of cooperation with the cutter in the 60 same way as the usual steel roll, but which, relative to each other, may yield bodily to compensate for substantial differences in thickness of the skin.

In my aforesaid application I have also disclosed a feed roll which acts merely to press the work against the cutter but which has no positive feeding action to advance the work relatively to the cutter. For some types of work it is desirable to employ a positive feed, 70 but on the other hand a constant drive of the feed roll is often annoying to the operator because it interferes with the proper adjustment of the work in making it ready for presentation to the cutter. In accordance with the 75 present invention I provide for positively driving the feed roll by the use of simple, sturdy, and efficient connections which are operative to drive the roll only when the roll is disposed in cooperative relation to the cutter. 80 85

In the accompanying drawings which illustrate certain desirable embodiments of the invention by way of example:

Fig. 1 is a front elevation, partly in section and partly broken away, of a leather shaving 90 machine embodying the present invention;

Fig. 2 is a vertical section on the line 2—2 of Fig. 1, but showing certain parts at the right-hand side of the machine in end elevation;

Fig. 3 is a fragmentary end elevation, showing portions of the mechanism at the left-hand side of the machine;

Fig. 4 is a section on the line 4—4 of Fig. 2 showing one desirable form of feed roll 100

but with certain features greatly exaggerated;

Fig. 5 is a front elevation of a modified form of feed roll; and

5 Fig. 6 is a section to larger scale on the line 6—6 of Fig. 5.

Referring to the drawings the main frame of the machine is indicated as comprising the left-hand and right-hand upright frame 10 members 1 and 2 which are united in any desirable manner to form a rigid support for the operating parts. The frame members 1 and 2 are provided with bearings for the shaft of a rotary shaving cutter 3. As here 15 shown this shaft extends to the right of the frame member 2 and is provided with a pulley 3^a which is driven by a belt B passing around a pulley P on the main drive shaft S which turns in bearings in the lower 20 rear part of the frame. The cutter 3 may be of any desirable type preferably employing a plurality of blades, and a grinding wheel 4 of usual type may, if desired, be provided for sharpening the cutter.

25 At a suitable point, preferably between the vertical plane of the cutter axis and the front of the machine, I arrange a horizontal shaft 5 mounted at its opposite ends in the frame members 1 and 2, and on this shaft mount an oscillatory frame carrying the feed roll support. Preferably this oscillatory frame 30 comprises the spaced side members 6 and 7 and the upper transverse bar 8. This bar is furnished with a swivel stud 9 upon which 35 is adjustably mounted the feed roll support 10. This support may be adjusted about the stud 9 by means of set screws 12. The feed roll support 10 is furnished with unyielding bearings for the shaft 13^a of the feed roll 13 40 and as normally adjusted, the shaft 13^a is substantially parallel to the axis of the cutter 3, the feed roll being disposed in front of the cutter and with its axis substantially in the same horizontal plane as the cutter axis. 45 For limiting movement of the feed roll support away from the cutter stop screws 16 are provided.

In order to swing the feed roll support 50 away from the cutter, the side members 6 and 7 are extended downwardly below the shaft 5 as shown at 18 and 19 respectively, and springs 20 and 21 are attached to these downwardly extending portions, the rear ends of the springs being attached to convenient 55 parts of the frame.

For moving the feed roll toward the cutter and for positively and unyieldingly holding it in operative position, I provide a toggle mechanism comprising the link 23 having its 60 rear end pivotally secured to the feed roll support 10 and having its forward end connected by a pivot pin 27 to the rear end of a second link 26 whose forward end is supported by pintles or trunnions carried by a 65 slide member 31. This slide member rests

upon the flat upper surface of a fixed table 32 and may be adjusted thereon by means of the threaded stud 36. For actuating the toggle device, I provide a connecting rod 39 whose upper end engages the pivot pin 27 and whose lower end is secured to a hook H attached to a treadle lever 40 having a foot rest 42 at its forward end. This treadle lever 40 is here shown as comprising laterally spaced members disposed adjacent to the frame members 1 and 2; respectively, with the foot rest 42 extending transversely across the machine, but it is to be understood that the treadle lever may consist of a single member and that the foot rest may be of such width as is desirable. The treadle lever, comprising the laterally spaced parts above referred to, is pivotally supported upon a shaft 41 which is journaled to turn in bearings in the frame members 1 and 2. The treadle lever 45 is free to turn relatively to this shaft, and its downward movement may, if desired, be limited by an adjustable stud 38.

Preferably the feed roll support 10 also carries a transverse shaft 43 provided with a work advancing roller 43^a and having a sprocket wheel 43^b at one end. An apron 44 extends forwardly and downwardly to protect the operator and to form a support for the work as the latter is advanced toward the feed roll.

In accordance with the present invention I provide means for driving the feed roll positively during the cutting operation and to this end I secure a sprocket wheel 45 to the drive shaft S, and this sprocket wheel drives a sprocket chain 46 which engages a sprocket 47 secured to the shaft 41. This shaft is provided at the left-hand side of the machine (Figs. 1 and 3) with a gear 48, and as the shaft S is constantly rotated while the machine is in operation, the gear 48 is likewise constantly driven. The frame member 1 supports a swinging link member 49 by means of a stub shaft 50, and this swinging link is provided with a stub shaft 51 (Fig. 3) on which is mounted, to turn freely, a gear 52 which has fixed thereto a sprocket wheel 53. The left-hand member of the treadle lever is provided with a pin 54 which projects outwardly through a slot 55 in the frame member 1 and into a hole 56 in the swinging link 49. This hole 56 is of slightly larger diameter than that of the pin. As the treadle lever is depressed, the link 49 is swung in a direction to cause the gear 52 to come into mesh with the gear 48 and to be driven by the latter. A sprocket chain 57 engages the sprocket wheel 53 and passes around a sprocket wheel 58 on the end of the shaft 120 13^a of the feed roll 13 and also about sprocket 43^b on the shaft carrying roller 43^a. Normally the gear 52 is disengaged from the gear 48, but when the operator has positioned the work between the feed roll and the cutter 125 130 135

and depresses the treadle to force the feed roll toward the cutter and to lock it in operative position, the downward movement of the threadle lever also brings the gear 52 into mesh with the gear 48 so that the feed roll is driven, thus feeding the work to the cutter in a uniform and positive manner. On the other hand, when the treadle is released to permit the feed roll to be retracted from the cutter, the gear 52 is moved out of mesh with the gear 48 and the rotation of the feed roll ceases, thus permitting the operator to adjust the work without interference from rotation of the feed roll.

To insure a clean cutting action it is desirable to make the diameter of the feed roll as small as possible so as to approximate a line contact with the cutter blades, while in dealing with certain types of work, it is desirable that the feed roll yield to a limited extent to avoid removing an undue amount of material from certain portions of the skin being shaved. As shown in exaggerated form in Fig. 4, the feed roll 13 is made of such small diameter that when the work W is substantially thicker at one part than another, for example at its longitudinal center line, the feed roll will spring away from the cutter. While such springing may be desirable, it is necessary to limit the amount of such spring and the position at which it shall take place in order to obtain a proper shaving action, and to this end I provide one or more normally fixed abutment members 60, here shown as consisting of blocks mounted to slide upon a supporting table 59 carried by the feed roll support 10. These blocks as here shown are individually adjustable toward and from the axis of the cutter by means of adjusting screws 63 engaging threaded openings in brackets 64 carried by the table 59. These abutment blocks 60 may be of any suitable material, for example of a bearing metal such as bronze, or iron lined with babbitt or, if preferred, they may be provided with recesses or other arrangements for holding anti-friction elements such as the balls 61 (Fig. 4). Preferably the faces of these blocks which are intended to bear against the feed roll are concave on an arc substantially concentric with the axis of the feed roll. Under some circumstances these abutments may be permanently fixed in position rather than adjustable, and one or more such abutments will be used as desired.

An alternative construction is shown in Figs. 5 and 6 wherein the feed roll shaft 13^b may be of stiff rigid material which will not spring substantially during the cutting operation, but is provided with a sheath 65 of yielding material, for example rubber, felt, etc., and of substantial thickness, and having a series of hard surfaced rigid rings 66 spaced longitudinally, and snugly embracing the sheath. These rings may be of steel, brass

or other suitable material adapted to cooperate in the same way as the usual metal roll in holding the work up against the cutter. This form of roll is also provided with the abutment blocks as above described, and while providing the desired hard work-engaging surface, is capable of yielding to a predetermined limited extent.

While I have herein shown and described certain desirable arrangements of parts useful for the purpose, I do not intend to restrict myself thereby to the specific arrangement illustrated, but regard all equivalent arrangements as falling within the scope of the invention.

I claim:

1. A leather shaving machine having a rotating cutter, a feed roll, and means for holding the end portions of the feed roll in substantially unyielding predetermined relation to the cutter during the shaving operation, the feed roll having a work-engaging surface which rigidly resists deformation from a true circular curvature, said roll being of such construction as to permit the work-engaging surface of the central part of the roll to spring away from the cutter to accommodate work of non-uniform thickness, and unyielding abutment means to limit the amount of such spring.

2. A leather shaving machine having a rotating cutter and a feed roll cooperating therewith, a shaft for the feed roll, normally fixed and unyielding bearings for the shaft, the feed roll being of such small diameter as compared with its length that it springs laterally intermediate the ends of the roll in response to abnormal pressure, and unyielding abutment means for limiting the amount of such spring.

3. A leather shaving machine having a cutter and a feed roll cooperating therewith, the effective surface of the feed roll being capable of yielding laterally at points intermediate the ends of the roll when subjected to abnormal pressure, said surface being in deformable from a circular curvature to ensure proper cooperation with the cutter and unyielding but adjustable abutment means for limiting such lateral yield.

4. A leather shaving machine comprising a cutter, a feed roll cooperating therewith, and substantially unyielding bearings for the feed roll, the feed roll being of so small diameter as compared with its length that its central portion yields laterally in response to abnormal pressure, and a plurality of unyielding abutments spaced longitudinally of the roll for limiting its lateral yield.

5. A leather shaving machine comprising a cutter, a feed roll cooperating therewith, and substantially unyielding bearings for the feed roll, the work-engaging surface of the feed roll intermediate its ends being laterally yieldable in response to abnormal pres-

sure, said surface being hard and indeformable from a true circular curvature, and an unyielding abutment for limiting lateral yield of the feed roll, said abutment comprising anti-friction means for contact with the surface of the roll.

6. A leather shaving machine comprising a cutter, a feed roll cooperating therewith, and substantially unyielding bearings for 10 the feed roll, the work-engaging surface of the feed roll intermediate its ends being indeformable from a true circular curvature and being laterally yieldable in response to abnormal pressure, and a plurality of unyielding abutments spaced longitudinally of 15 the roll for limiting its lateral yield, said abutments being independently adjustable.

7. A leather shaving machine having a cutter and a feed roll comprising a core, a 20 sheath of resilient material surrounding the core, and a plurality of substantially hard surfaced rings embracing the sheath and collectively constituting the effective surface 25 of the roll, and unyielding abutment means associated with said roll for limiting the eccentricity of said rings relative to the axis of the roll.

8. A leather shaving machine having a cutter and a feed roll, means for moving the 30 feed roll into and out of cooperative relation to the cutter, means including a pair of cooperating gears and a sprocket chain for driving the feed roll, said gears intermeshing to drive the roll only when the roll is disposed in cooperative relation to the cutter.

9. A leather shaving machine having a cutter and a feed roll, means for moving the feed roll into and out of cooperative relation 40 to the cutter, said means comprising a treadle, and means for driving the feed roll comprising normally separated gears which are brought into cooperative relation when the treadle is actuated to move the feed roll into cooperative relation to the cutter, and a sprocket chain for transmitting motion 45 from the driven gear to the roll.

10. A leather shaving machine having a cutter and a feed roll, means for moving the feed roll into and out of cooperative relation 50 to the cutter, said means comprising a treadle lever, means for driving the feed roll comprising a gear coaxial for the treadle lever and a second gear normally out of mesh with said first gear, and means actuatable by the treadle lever when the latter is moved to bring the roll into cooperative relation to the cutter for causing said second gear to mesh with the first gear.

11. A leather shaving machine having a 60 cutter and a feed roll, means for moving the feed roll into and out of cooperative relation to the cutter, said means comprising a treadle lever, means for driving the feed roll comprising a gear coaxial for the treadle 65 lever, a link member supporting a second

gear cooperative with the first gear but normally out of mesh with the latter, and connections between the treadle lever and the link member such that, when the treadle is actuated to bring the roll into cooperative relation to the cutter, the second gear is brought into driving relation to the first.

12. A leather shaving machine having a cutter and a plurality of work advancing rolls, means for moving said rolls toward 75 and from the cutter, said means comprising a treadle lever, means for driving the rolls comprising a gear coaxial with the treadle lever, means for driving the gear continuously, a second gear normally out of mesh 80 with the first but cooperable therewith, connections for transmitting motion from the second gear to the rolls, and means actuated by the treadle lever, when the latter is moved to advance the rolls toward the cutter, for 85 moving the second gear into mesh with the first gear.

Signed by me at Boston, Massachusetts, this 29th day of January, 1930.
